T. A. DICKINSON.
SELF FILLING FOUNTAIN PEN.
APPLICATION FILED DEC. 22, 1919.

1,346,184.

Patented July 13, 1920.

UNITED STATES PATENT OFFICE.

THOMAS A. DICKINSON, OF YOUNGSTOWN, OHIO.

SELF-FILLING FOUNTAIN-PEN.

1,346,184.

Specification of Letters Patent. Patented July 13, 1920.

Application filed December 22, 1919. Serial No. 346,707.

To all whom it may concern:

Be it known that I, THOMAS A. DICKINSON, a subject of the King of Great Britain, residing at Youngstown, in the county of 5 Mahoning and State of Ohio, have invented a new and useful Self-Filling Fountain-Pen, of which the following is a specification.

This invention relates to improvements in fountain pens and has more especial reference to a self-filling fountain pen formed of 10 transparent material in order that the user may see the amount of ink contained in the pen.

The objects of the invention are to provide 15 a pen of transparent material through which the ink contained within the barrel of the pen will always be visible; to provide a self-filling fountain pen containing a minimum number of parts; and to provide a fountain 20 pen of this character which is simple and inexpensive to manufacture and efficient in use and arranged to use up the last drop of ink contained within the barrel thereof.

With these objects in view the invention 25 consists in the novel construction and arrangement of parts, hereinafter described, illustrated in the accompanying drawings, and particularly pointed out in the appended claims, it being understood that various 30 changes in the form, proportions, size and minor details of construction may be made within the scope of the appended claims, without departing from the spirit or sacrificing any of the advantages of the invention. 35

The invention thus set forth in general terms is illustrated in the accompanying drawings forming part hereof, in which—

Figure 1 is a longitudinal sectional view 40 through a pen employing the invention showing the same ready for use.

Fig. 2 is a similar view showing the operation thereof for filling, and

Fig. 3 is a perspective view of the end portion of the barrel.

A practical embodiment of the invention is disclosed in the accompanying drawings, forming a part of this specification in which similar numerals of reference indicate corresponding parts throughout the several views.

The barrel 1 of the pen is preferably formed of a suitable transparent material and although the barrel is illustrated in the drawings as made of one piece it will be 55 understood that this barrel may be made of one or two pieces in order to form it of

different materials. The lower or writing end of the barrel is reduced and provided with the usual neck portion 2 having mounted therein the protruding nozzle 3 which 60 carries the pen point 4 slotted at 5 in the usual manner.

Attention is directed to the channel 6 in the nozzle. This channel extending through the longitudinal center of the nozzle instead 65 of being located directly beneath the pen in the usual manner. This channel extends to the hole 7 in the pen point which is located at the upper end of the slot therein and the pen nib does not project into the ink channel 70 of the pen, the upper end 8 of the nozzle fully closing the ink chamber.

The advantage gained with this form of nozzle is that the pen will use the last drop 75 of ink in the ink channel and as the channel 6 extends downwardly to the hole 7 in the pen point ink may be drawn into the ink chamber of the pen from a lower level than is possible with the ordinary type of self filling fountain pens.

The rear or upper end of the pen is provided with the end wall 9 having the conical valve seat 10 therein, a reduced externally threaded neck 11 protruding beyond said end wall. This neck is provided with longitudinal grooves 12 extending from the usual end thereof to a point near the lower or inner end of the threads and a cap 13 is threaded upon the neck and arranged to normally fit snugly against the rear end of the barrel portion of the pen, thus closing the 80 grooves 12.

A rubber disk 14 is cemented or otherwise securely attached to the inner face of the cap and cemented or otherwise connected within 95 the cap is the stopper 15 provided with a conical valve 16 arranged to normally close the upper or rear end of the ink chamber by seating within the valve seat 10.

The barrel of the pen is provided near its 100 upper or rear end with a rubber washer 17 which is cemented or otherwise secured within the annular groove 18 in the barrel portion of the pen. The usual cap 19 is provided for the pen and provided with the 105 internal screw threads 20 arranged to engage the threads 21 upon the lower end of the barrel in order to protect the pen point when not in use.

This cap is arranged to fit loosely over 110 the rear end of the barrel of the pen as shown in Fig. 1, the washer 17 engaging the

interior of the cap and fitting snugly therein forming an air tight joint between the pen barrel and the cap.

An aperture 22 is provided in the cap 19 near the rear or lower end thereof. A plurality of annular grooves 23 is formed around the interior of the neck portion 11. These grooves are provided as an additional precaution to prevent any ink which might 10 creep around the valve 16 from passing through the grooves 12 and through the aperture 22 and upon the operator's fingers when the pen is being filled.

The operation of the device is as follows: 15 When it is desired to fill the pen the inner cap 13 is unscrewed sufficient to uncover the grooves 12 formed in the neck portion 11 of the pen at the same time unseating the valve 16 from its seat 10. The chamber or 20 interior of the barrel of the pen is thus opened to the outer atmosphere through the valve 16 and grooves 12.

The cap 19 is then placed upon the end of the barrel in the position shown in Fig. 1 25 and is grasped by the operator, one finger being covered over the aperture 22. The nozzle 3 is then inserted into the bottle or other receptacle from which the ink is to be withdrawn and the cap 19 is withdrawn from 30 the end of the barrel sucking the ink up through the nozzle and into the barrel of the pen.

The cap 13 is then screwed down into place closing the valve 16 and the pen is 35 ready for use. When writing with the pen the cap 13 may be partially unscrewed to allow atmospheric air to enter the upper

end of the ink chamber causing a freer flow of ink at the pen point. All of the parts of the pen are made of transparent material 40 with the possible exception of the gold pen point, the rubber washer 17 and the rubber cushion or disk 14.

Although the drawings and above specification disclose the best mode in which I 45 have contemplated embodying my invention I desire to be not limited to the details of such disclosure, for, in the further practical application of my invention, many changes in form and construction may be 50 made, as circumstances require or experience suggests, without departing from the spirit of the invention, within the scope of the appended claim.

I claim:

A self-filling fountain pen comprising a barrel portion having an aperture in its rear end and a threaded reduced neck extending beyond its rear end, said neck being provided with longitudinal grooves in its outer 60 surface, a screw threaded cap fitting upon said neck and normally closing said grooves, the interior of said neck being provided with annular grooves, a valve carried by said cap and arranged to close the aperture in the 65 end of the barrel, a resilient peripheral washer located around the barrel and an elongated cap arranged to slide over the rear end of the barrel and tightly fitting upon said washer.

In testimony that I claim the above, I have hereunto subscribed my name.

THOMAS A. DICKINSON.
